HOSE SUPPORT

Charles E. Burns, Collingswood, N. J.

Application March 19, 1935, Serial No. 11,767

11 Claims. (Cl. 299—77)

This invention relates to hose supports, and it has reference more particularly to means for supporting hoses for convenience of manipulation incident to spray washing locomotives, railroad cars and other relatively large and long objects.

In washing locomotives or railroad cars, for example, it has been the custom heretofore to employ long spray hoses which extended from a water supply connection and which had to be dragged back and forth along the ground for access to different parts of the locomotives or cars with the spray nozzles. Such dragging obviously caused rapid wear and necessitated frequent re- placements of the hoses. Moreover, in order to avoid the strenuous exertion involved in moving about the hoses, the operatives, unless under close supervision, would invariably stand in a fixed position and direct the water spray onto the locomotives or cars from a distance. Under these circumstances, the washing was far from being thorough and satisfactory, notwithstanding the use of a great amount of water in the operation.

Considered from the broadest aspect, my invention is directed toward overcoming the drawbacks which are pointed out above. This objective I realize as hereinafter more fully set forth, through provision of a hose supporting means including an arm from the end of which the hose is suspended, and which is pivotally supported with capacity to swing in a vertical plane through an arc of approximately 180° from a substantially horizontal position at one side of the post to a substantially horizontal position at the other side of the post, said arm being slightly counterweighted for maintenance normally in upright position. For the purposes of locomotive or railroad car washing, I employ, as also more fully set forth hereinafter, two of such hose supporting means, one at each side of a track siding with the pivots arranged for swinging of the hose supporting arms in vertical planes parallel to the track rails.

Other objects and attendant advantages will be manifest from the following detailed description of the accompanying drawings; wherein, Fig. I is a view in side elevation showing hose supports of my invention arranged for locomotive washing.

Fig. II is a plan view of the organization shown in Fig. I.

Fig. III is a fragmentary view on a larger scale showing one of the hose supports in side elevation.

Fig. IV is a plan view of the support.

Fig. V is a fragmentary sectional view taken as indicated by the arrows V—V in Figs. III and IV and drawn to a still larger scale; and,

Fig. VI is a detail sectional view taken as indicated by the arrows VI—VI in Fig. IV.

With more detailed reference first to Figs. I and II of these illustrations, T designates a railway track siding onto which the locomotive L to be cleaned is run centrally between a pair of hose supports 1 which are identical in construction and symmetrically disposed at opposite sides of said track siding. Each of the hose supports 1 comprises a post 2 to the upper end of which is pivoted an arm 3 with capacity to be swung vertically in a plane parallel to the track T through an arc of approximately 180° from a substantially horizontal position 3a (Fig. I) at one side of the post, to a corresponding position 3b at the opposite side of said post.

As shown in Figs. III and IV, the arm 3 is of composite construction comprising a tubular portion 4 and a bifurcate fulcrum portion 5 meeting in a juncture block 6 and held assembled by clamp bolts 7. The spaced extremities 8 of the bifurcate portion 5 of the arm 3 straddle the post 2 and are apertured as at 9 to engage over the ends of an axis member 10 secured transversely of the post 2 near the top. From Fig. V it will be observed that the axis member 10 has axial hollows 11, 12 at opposite ends thereof. Connecting into the hollows 11 and 12 of the axis member 10 at the top are supply pipes 13 and 14 which extend respectively from sources of water or other washing liquid and compressed air (not illustrated), said pipes having suitable control valves 15 and 16 interposed in them. Extending through the tubular portion 4 of the arm 3 is a water conducting pipe 17 with an angled branch 18 whereof the end 19 connects axially into the hollow 11 of the axis member 10 through a stuffed swivel joint 20. As further shown in Figs. III and IV, the water conducting pipe 17 extends somewhat beyond the outer end of the tubular section 4 of the arm 3 and terminates in an elbow 21. Connected by a swivel joint 22 to the elbow 21 is another elbow 23 to which a suspended flexible hose 24 is connected, said hose being substantially the same length as the arm 3 and fitted at its free end with a nozzle 25. The extremities 8 of the bifurcated portion 5 of the arm 3 extend well beyond the fulcrum axis, and, at their swinging ends, carry weights 26 which slightly overbalance the weight of the hose 24 and thus tend to keep the arm 3 normally

in upright position as shown in dotted lines at 3c in Fig. I. Also extending through the tubular portion 4 of the arm 3 is an air pipe 27 having an angled branch 28 whereof the end 29 connects axially with the end cavity 12 of the axis member 18 through a stuffing box 30. Beyond the end of the arm 3, the pipe 27 enters the pipe 17 at an angle as at 31, so that the compressed air is injected into the pipe 17 in the direction 10 of the flow of the water therein. With the aid of the compressed air, the water is forcibly expelled from the nozzle 25 of the hose 24, and is thus made more effective in removing mud and dirt accumulations from the locomotive L or 15 car being washed.

In the use of my invention, by grasping the nozzle 25 of the hose 24 at either side of the track siding T, the operative can walk the entire length of the locomotive L without having to drag the 20 hose 24 or to support the weight thereof, the only resistance to the attendant movement of the arm 3 being that due to the small excess weight of the counterweights 26. All parts of the locomotive L are thus made available for cleaning at close 25 range so that the cleaning operation can be accomplished in much less time than required heretofore. The washing operation is further expedited and rendered more economical with the aid of compressed air, since under the forcible 30 action of the latter, dirt and mud are effectively loosened so that less water is required for their removal.

While I have herein particularly shown and described my novel hose supports in duplicate for 35 the purposes of locomotive or car washing, it is obvious that they may be employed singly in other connections without departing from the spirit of my invention as defined in the broader of the following claims.

40 Having thus described my invention, I claim:
1. A hose support comprising a rigid post; a tubular arm pivoted by a bifurcate fulcrum portion to the post upper end with capacity for free 45 swinging movement in a vertical plane through an arc of approximately 180° from a substantially horizontal position at one side of the post to a corresponding position at the other side of the post; a fluid-conducting conduit in the tubular arm; and a hose swivelly suspended from the outer end of said conduit.

50 2. A hose support in accordance with claim 1, wherein the tubular arm has a bifurcated fulcrum portion straddling the post, with the inner parts of said fulcrum portion apertured to engage 55 the opposite ends of a stationary axis member extending transversely of the post at the top.

3. A hose support in accordance with claim 1, wherein the tubular arm has a bifurcated fulcrum portion straddling the post with the inner 60 parts of said fulcrum portion apertured to engage the opposite ends of an axis member fixed transversely of the top of the post, and the outer parts of said fulcrum portion extending beyond the fulcrum axis carry individual counterweights to 65 slightly overbalance the weight of the hose whereby said arm is normally maintained in upright position.

70 4. A hose support comprising a counterweighted tubular arm; a fixed axis on which said arm is pivoted by a bifurcated extension; a pipe passing through and somewhat beyond the arm outer end by which fluid is conducted from the region of the pivot axis; and a hose swivelly connected by elbow means to the outer end of said pipe.

5. A hose support comprising a counterweighted tubular arm pivoted with capacity for free swinging movement in a vertical plane by a bifurcated extension at one end; a pipe passing through and somewhat beyond the outer end of the arm by which fluid is conducted from the region of the pivot; an elbow at the outer end of said pipe with an attached swivel joint and second elbow; and a hose suspended from said second elbow for capacity to be swung in a parallel 10 plane.

6. A hose support comprising a counterweighted tubular arm; a fixed axis on which said arm is pivoted by a bifurcated extension at one end; a pipe through said arm by which water is conducted from the region of the pivot to the outer end of the arm; a hose swivelly connected to the outer end of the pipe; and another pipe through the arm for conducting compressed air from the region of the pivot to a point within the water pipe adjacent the outer end thereof to accelerate 20 discharge of the water through the hose.

7. A hose support comprising a counterweighted tubular arm; a fixed axially-hollow axis member at the top of a rigid post to which the 25 arm is pivoted, said axis member being connected to a source of fluid supply; a conducting pipe through said arm having the inner end thereof swivelly connected by an angled bend axially with the hollow axis member; and a 30 hose connected by elbows with an intervening swivel-joint to the outer end of the conducting pipe.

8. A hose support comprising a counterweighted arm; a fixed axis member on which 35 said arm is pivoted, said member having axial hollows in opposite ends thereof, one connected to a source of water supply and the other connected to a source of compressed air supply; a water conducting pipe along the arm having its inner 40 end connected axially with the corresponding end hollow of the axis member; a compressed air conducting pipe also along the arm similarly connected with the other end hollow of the axis member and terminating at its outer end within the 45 water conducting pipe adjacent the outer end of the latter; and a hose connected to the outer end of the water conducting pipe.

9. A hose support in accordance with claim 8 to support hose for wash water at opposite sides 50 of a railroad track wherein the hose supporting arms are respectively adapted for free swinging movement in planes parallel to the track through an arc of approximately 180° relative to the horizontal.

55 10. A hose support in accordance with claim 8 to support hose for wash water at opposite sides of a railroad track wherein the hose supporting arms are respectively adapted for free swinging movement in planes parallel to the track through 60 an arc of approximately 180° relative to the horizontal, and wherein counterweight means slightly in excess of the weight of the hose causes the arm to be normally maintained in upright position.

65 11. The combination with a railroad track siding for locomotives and the like; of means in accordance with claim 8 to support hose for wash water at opposite sides of the track, and wherein in the hose supporting arms are respectively 70 swingable in planes parallel to the track.

CHARLES E. BURNS.
